UNITED STATES PATENT OFFICE.

ROBERT MELVILLE SCOTT, OF BALMAIN, NEAR SYDNEY, NEW SOUTH WALES.

APPARATUS FOR REMOVING HARBOR AND RIVER BARS AND SHOALS AND PREVENTING THE FORMATION OF THE SAME.

SPECIFICATION forming part of Letters Patent No. 510,713, dated December 12, 1893.

Application filed December 9, 1891. Serial No. 414,509. (No model.)

To all whom it may concern:

Be it known that I, ROBERT MELVILLE SCOTT, a subject of the Queen of Great Britain, residing in Balmain, near Sydney, New 5 South Wales, have invented new and useful improvements in apparatus for removing harbor and river bars and shoals and subaqueous sand-banks and other deposits of like nature and preventing the formation of the 10 same, for deepening and widening rivers and cutting and clearing canals and like water-courses through sand, clay, earth, and similar formations, and for maintaining a channel in rivers, canals, races, and other water courses; 15 and I do hereby declare the following to be a full, clear, and exact description of the invention, such as will enable others skilled in the art to which it appertains to make and use the same.

20 This invention relates to the removal of bars and shoals from harbor and river entrances and estuaries; to the removal of sand and mud banks and like deposits from harbors, rivers, and estuaries; to the prevention 25 of the formation of such bars, shoals, banks, and deposits; to the deepening and widening of rivers and creeks, and to the cutting and clearing of canals and similar watercourses through sand, clay, earth, and formations of 30 a like nature, and to the maintaining of a channel in rivers, canals, races, and other watercourses in which the speed of the water is insufficient to carry away sand, mud, and tailings, and like solid matters which pass into 35 the same.

That part of the invention which relates to the removal of bars, banks, and shoals in harbors, rivers, and estuaries, and to the maintaining of channels and watercourses, consists 40 in the employment of a permanent water service pipe or pipes, provided with nozzles, and set upon or under or contiguous to the obstruction. The removal and clearing is effected by the action of the jets of water which 45 are forced out through the nozzles under pressure, and disturb, loosen, break-up, and agitate the sand, mud, silt, or other deposit, converting it into a species of quicksand or sludge and causing it to be held in suspension or floated in the water and carried away

with the stream, or, if the jets should be set obliquely, in the current of water which they induce. In lieu of a permanent service a movable or temporary pipe line or lines may be provided capable of being moved about 55 and temporarily fixed by anchoring, guying, or otherwise. Such a device is intended especially for operating on bars, banks, and shoals whose position is not permanent but shifting, or through which it is required only 60 to open or to maintain a temporary channel. In some cases I secure the service pipes to hollow floats, which are all connected to suitable pumping gear, whereby they may be filled with or discharged of water, in order that 65 they with their attachments might be sunk onto the place being operated upon, and lifted again to the surface as may be required. When the construction is not permanent, the joints or couplings of the service pipes are 70 made flexible.

When a permanent channel is required through any obstruction of the kind described which is liable to be reformed through the operation of a water scour or other natural 75 cause, a channel is first cut to the necessary depth, or if it should be thought advantageous, deeper than is actually necessary, by means of apparatus of the kind described or otherwise; and then midway, or approximately so, on the 80 bar, bank, shoal, or other obstruction, or contiguous thereto, piles are driven to a firm footing; upon these piles the permanent service pipes are secured. A clear passage may be maintained through any obstruction of the 85 kind described by pumping the water while the tide is ebbing or while a fairly fast outward current continues to flow. The water jets will induce a current if the nozzles are fixed obliquely on the pipe, and the current 90 thus induced will float or carry away by action the solid particles which have been forced up by the jets. During the flow of the tide, and while the water is sluggish, pumping may be discontinued, and re-commenced 95 at the turn of the tide or the start of the stream. Where the obstructions are not quickly formed it may be found sufficient to carry on pumping operations periodically.

When continuous pumping is not main- 100

tained, clack valves may be fitted to the nozzles; and when pumping is discontinued the pipes are exhausted of air so as to form a total or partial vacuum within them, whereby the 5 valves are made to close tight and prevent the entrance of mud, sand and like matters into the pipes.

In operating upon a bar, shoal, bank, or other deposit of considerable length and area, 10 I prefer to use two or more service pipes each connected to separate sources of supply, so that any one of them can be operated independently of the others. In this way it is possible to confine operations to any particular section.

Where a stream or race or water course runs too slowly to carry off the solid matter which passes into it, a pipe is laid into the bed and pumping carried on continuously or at intervals as may be required; an artificial bottom current of considerable speed is thus induced which sweeps the solid matter toward the end of the pipe toward which the jets are directed.

25 In cases where the service pipe is of considerable length or where it is armed with a large number of nozzles, feeder pipes may be led into it at convenient points.

The pressure under which the water is 30 forced may vary within wide limits. Deposits of material of very light gravity may be removed by comparatively light streams of water under light pressure; but banks and shoals of material of heavy gravity will require a considerable quantity of water under 35 high pressure.

The nozzles on pipes may be set so as to discharge jets of water at right angles to the length of the pipe, or at any desired angle relatively thereto, either up or down stream. The number and size of the nozzles and their disposition may also be varied. The pipes shown in the drawings are armed with nozzles on both sides and on the top.

45 The most advantageous and economical method of application of the invention in any particular case will depend upon local circumstances and requirements, and the precise method employed of carrying out the 50 invention may therefore be varied within wide limits according to the judgment of a person sufficiently skilled.

While my invention is primarily designed to operate on submerged earth formations 55 such as sand banks bars and the bottoms of channels which have filled up, cases might arise in which it could be advantageously applied to the removal of earth which is not submerged. Its greater value, however, is in its first application, in assisting and directing the action of natural forces in stirring up the bottom of a moving body of water so that the natural flow of the current can carry off the material.

65 While I have illustrated but one water forcing apparatus, namely, a steam pump,

others might be used, such as a natural water power, a tide mill, the flow of impounded tide water, &c.

Referring to the annexed sheet of explanatory drawings, Figure 1 is a plan of a river mouth showing the general arrangement of the clearing pipes and their position upon the bar; Fig. 2 a section showing a permanent pipe line; Fig. 3, a section showing a floating pipe line. Fig. 4 is a side elevation, enlarged, of a flexible jointed pipe; Fig. 5 a side elevation of a fragment of a service pipe with an auxiliary feed pipe, and shows the method of operating service pipe. Fig. 6 is a transverse section through the pipe and sleeper shown in the previous figure. Fig. 7 is a detail view of a nozzle showing the outwardly opening valve. Fig. 8 is a modification in which the air pipes are connected to the highest portion of each float.

The arrangement of pipes as shown in Fig. 1 of the drawings may be varied at will. The service pipes as shown in Figs. 1 and 2 are provided with nozzles, such as 8, Fig. 4, 90 which are set obliquely so as to deliver the jets of water angularly and thus, while disturbing and breaking up the sand, mud, or other deposit, they produce an artificial under current which sweeps the broken up substances toward the end of the pipe.

In the arrangement shown in Fig. 3, 2 are boxes, barrels or like hollow floats; 3, an air pipe; 4, flexible connecting pipes; 5, hanging chains; 6, a service pipe; 7, flexible couplings; 8, nozzles; 9, bank or shoal being operated upon. The flexible pipes 4 which connect the boxes are so arranged that when pressure is applied the water is driven out of each vessel successively, thus floating it, and when pressure is withdrawn or vacuum formed, the water may enter each successively and sink it. 105 16, is the pumping station. In laying such a system, the vessels, empty, are floated into position, with the service pipes suspended by the 110 chains, clamps, or like attachments 5, and then the vessels are allowed to fill and sink into the position shown. The number and size of the jets may be varied with the description of work being done. When the obstruction is 115 slow forming, a few jets may be found ample; but when the quantity to be removed is considerable, a proportionate water service must be used. 20 are the sinking tanks. 19 is the 120 steam pump, which connects with both the nozzles and the tanks.

Referring to Figs. 6 and 7, 10 is a service pipe; 11 a bearer of sleeper; 12 a perforated pipe or casing secured to the under part of the sleeper; 13 orifices therein; 14 a supply pipe leading thereto; 18, an auxiliary feed pipe to main water pipe. When water under pressure is supplied to the pipes or castings 12, the underlying sand, mud, and other deposit is removed by the action of the jets; the whole 130 construction then sinks until a solid bottom is reached. The pipes 14 may then be dis-

connected. When branch pipes are to be added to mains already existing they are sunk in a similar manner.

In the construction shown in Fig. 3, the water in all the floats 2, has to pass out through that float farthest from the pumping station, so that the floats are emptied and rise successively, beginning with that one nearest to the pumping station.

10 In the modification shown in Fig. 9, the air pipes are connected to the highest portion of each float, and each float is provided with an outlet 15, at its lowest portion. When the air pressure is put on, the water is simultaneously forced out of each float through the openings 15, and they rise simultaneously. In each of the nozzles may be placed a spring valve, 17, opening outward.

15 The method of operating my invention has been clearly set forth in the preceding portions of the specification.

Although I have described and illustrated several constructions of apparatus to be employed in the carrying out of my invention, 20 and make specific claims for such apparatus, I would have it understood that I do not in any way restrict myself to the use thereof precisely as set forth.

I am aware that it is well known that earth banks may be cut down and swept away by the action of jets of water under pressure directed against them, such a method being commonly known as "hydraulicking;" and therefore I wish the claiming clauses following to be read restrictively in so far as such previous knowledge would prevent a broad interpretation being allowed them.

Having, therefore, described my invention, what I claim as new, and desire to protect by Letters Patent, is—

1. The combination of a submerged system of stationary water pipes, a plurality of nozzles arranged along each pipe and all slanting toward one end thereof, together with a water forcing apparatus connected with said system, substantially as described.

2. The combination of a submerged pipe, one or more sleepers for said pipe, a perforated casting on the bottom of the sleeper, a pipe connected with said casting and a water forcing apparatus connected with said pipe, substantially as described.

ROBERT MELVILLE SCOTT.
